UNITED STATES PATENT OFFICE.

IVAN M. TULL, OF CINCINNATI, OHIO, ASSIGNOR TO THE AMERICAN LAUNDRY MACHINERY COMPANY, OF CINCINNATI, OHIO, A CORPORATION OF OHIO.

WASHING MACHINE.

Application filed March 31, 1921. Serial No. 454,151.

This invention relates to improvements in washing machines.

More particularly, the present improvement relates to the type of washing machine commonly used by dry cleaners and laundries, that is, the type in which the perforated cylinder is enclosed within the casing and is given a rocking or oscillating motion through the cleansing fluid contained within the casing. Experience has shown that in the operation of this type of device the lint and dirt which are freed from the materials during the cleansing operation are circulated and re-circulated through the same by the agitation of the fluid below the cylinder with the result that the materials are not thoroughly cleaned and furthermore the materials are subjected to more or less wear due to the grinding action of the particles of foreign matter.

It is the object of this invention to provide means for minimizing circulation of such foreign matter through the materials by retarding the agitation of the cleansing fluid in the casing below the cylinder; also to provide a chamber in the lower portion of the casing within which the foreign matter will be allowed to settle by gravity, as quietly as possible and to be drawn off whenever desired; to provide means for separately drawing off the upper and lower parts of the cleansing fluid; also to provide means whereby the device for retarding agitation or parts of the same can be readily removed from the washing machine; and also to provide suitable openings for cleaning or flushing the sediment collecting chamber.

Other objects of this invention will appear from the following description and claims when considered in connection with the accompanying drawings.

Fig. 1 is an end elevation of the washing machine with parts broken away; Fig. 2 is a vertical longitudinal section of the washing machine taken on line 2-2, Fig. 1, with parts shown in elevation; Fig. 3 is an end elevation of a portion of one of the heads of the washing machine showing the opening for removing the baffle plates; Fig. 4 is a horizontal section taken on line 4-4, Fig. 1; Fig. 5 is a perspective detail view of the baffle plates; Fig. 6 shows in detail the locking engagement between the baffle plates; Fig. 7 shows a modified form of engagement between the baffle plates; Fig. 8

is a detail view of the notch engagement in Fig. 7.

The casing 1 provided with the usual supporting frame 2 enclosing the perforated cylinder or drum 3, the casing and drum being provided with doors 4 and 5, respectively, through which the materials can be loaded and unloaded. A clean-out door 6 is also provided in the drum and has sliding engagement in the guideways 7 for opening and closing. Latches 8 are also provided. As usual in this type of device, the drum is provided with a number of baffle members as indicated at 9 and is provided with mechanism for rocking or oscillating the drum in a back and forth motion. Such mechanism is here indicated in a general way by the gear 10 upon the gudgeon 11 at one end of the drum, the pinion 12 mounted upon the drive shaft 13 and meshing with the gear 10, the drive shaft receiving its power through the pulley and belt connection 14 and 15, respectively. The pipe connection 16 is provided for supplying the cleansing fluid to the casing. As usual in this type of device, the drum 3 being suitably perforated will allow circulation of the cleansing fluid from the lower portion of the casing to the materials within the drum.

In the present device, I have provided the casing 1 with a trough or chamber defined by the downwardly extending wall portions 17, the rest or shoulder portions 18 and the downwardly extending wall portions 19. The shoulder portions 18 serve as a rest for the rectangular frame member 20 within which are mounted the transverse baffle plates 21 secured thereto by the riveted flange portions 22, and the removable longitudinal baffle plates 23 which have notched engagement with the plates 21. The notched engagement between the longitudinal and transverse baffle plates is similar to that commonly found in egg crate partitions and is illustrated in Fig. 6. These parts are so formed that the contour of the top surface of the baffle means is approximately concentric with the axis of rotation of the cylinder 3; or in other words, the top of the baffle means is substantially a continuation of the casing wall.

The draw-off pipe 24 with the valve control 25 is provided in the end wall of the casing at approximately the same level as the top of the baffle means for the purpose of

drawing off that portion of the cleansing fluid, as for instance, gasolene, which is free from sediment and which therefore can be used again without clarifying; in other words, the "cream" of the cleansing fluid is drawn off through the pipe 24. The drain pipe 26 with the valve control 27 is provided in the bottom of the casing and at the lower portion of the incline 28. This drain is for the purpose of drawing off the fluid which will require clarification before being used again. Openings 29 and 30 are provided at opposite ends of the casing with the fluid tight closure plates 31 and 32, respectively, secured by bolts or other suitable means. Thus it will be seen that after the "cream" of the cleansing fluid has been drawn off through the pipe 24 and the bottom portion of the trough has been drained through the pipe 26, it is possible to remove the closures 31 and 32 and to flush the bottom of the trough or remove the sediment by means of a scraper. It is also possible to remove the baffle means in its entirety through the opening 30 and to replace the same after cleaning. Furthermore, the longitudinal baffle plates can be removed through the top of the casing upon bringing the doors 5 and 6 in register with the door opening 4.

According to the modification in Fig. 7, the frame 35 is entirely open at one end, or in other words, is of U-shape rather than a closed rectangle. Transverse members 36 and 37 extend across the frame 35 and are secured thereto in the same manner as described in connection with the main form of my device. The longitudinal baffle plates 38 have their lower edges tapered or inclined as at 39, their reduced end portions extending through the slots 40 provided in the transverse members 36, while the notches 41 at their other ends lock over the other transverse members 37. It will be seen that the longitudinal baffle plates can be separately removed either through the top of the casing or through the opening 30; in the latter case it being merely necessary to lift up the notched end portion so as to clear the notch 41 of the transverse member 37, whereupon they can be withdrawn. Sufficient space is provided between the baffle means and the drum to permit the raising of the plates in the unlocking operation as just now described.

Having described my invention, I claim:

1. In a machine of the character described, the combination of a casing, a rotatably mounted cylinder in said casing, said casing being provided with a trough beneath said cylinder, said trough being provided with a rest, means supported upon said rest for retarding agitation of the washing or cleaning fluid in said trough, means for drawing off the fluid to a level corresponding approx-

imately with the top of said agitation retarding means, and means for draining said trough.

2. In a machine of the character described, the combination of a casing, a rotatably mounted cylinder in said casing, a baffle means including removable baffle plates for retarding agitation of the washing or cleaning fluid outside of said cylinder, and means whereby either the said baffle means or the removable plates alone can be removed from said casing.

3. In a machine of the character described, the combination of a casing, a rotatably mounted cylinder in said casing, said casing being provided with a trough below said cylinder, and means including separably interlocked baffle plates for retarding agitation of the washing or cleaning fluid in said trough so as to permit deposit of foreign matter therein.

4. In a machine of the character described, the combination of a casing, a rotatably mounted cylinder in said casing, said casing being provided with a trough in its bottom, and means in said trough for retarding agitation of the washing or cleaning fluid, said casing being provided with an opening for removal of said means and with another opening in the wall of said trough at a lower level for removal of sediment.

5. In a machine of the character described, the combination of a casing, a rotatably mounted cylinder in said casing, and means for retarding agitation of the washing or cleaning fluid outside of said cylinder, said cylinder being provided with a loading door and a clean-out door, and said casing being provided with a loading opening and an opening for removal of said agitation retarding means, said doors and openings being so arranged as to permit removal of said agitation retarding means either through casing loading opening or through said other casing opening.

6. In a machine of the character described, the combination of a casing, a rotatably mounted cylinder in said casing, baffle means for retarding agitation of the washing or cleaning fluid outside of said cylinder, said baffle means including baffle plates, and means for removably locking said plates in position.

7. In a machine of the character described, the combination of a casing, a rotatably mounted cylinder in said casing, baffle means for retarding agitation of the washing or cleaning fluid outside of said cylinder, said baffle means including a frame, baffle plates, and means for removably locking said plates in said frame.

8. In a machine of the character described, the combination of a casing, a rotatably mounted cylinder in said casing, baffle means for retarding agitation of the washing or

cleaning fluid outside of said cylinder, said baffle means including an open-end frame, baffle plates, and means for removably locking said plates in said frame upon application thereto through the open end of said frame, said baffle means being spaced from said cylinder so as to permit application and removal of said plates.

9. In a device of the class described, a baffle means comprising an open-end frame having slotted transverse baffle plates, and tapered longitudinal baffle plates adapted to be applied through the open end of said frame and to have their tapered end portions seat in the slots of said transverse plates, and said longitudinal plates being provided with slots for interlocking engagement at their other ends with the slots of said transverse plates.

10. A machine of the character described, comprising a casing, a rotatable cylinder therein, and baffle means within the casing below the cylinder adapted to retard agitation of the cleansing fluid, said cylinder being provided with a loading door and a clean out door providing access through the cylinder to said baffle means.

11. A machine of the character described, comprising a casing, a rotatable cylinder therein, said casing being provided with a trough forming a chamber beneath the cylinder, baffle means in said chamber, and said cylinder being provided with a loading door and a clean out door permitting access through the cylinder to said chamber.

12. A machine of the character described, comprising a casing, a rotatable cylinder

therein, and baffle means within the casing below the cylinder, said casing being provided in a side wall with an opening through which said baffle means may be horizontally removed, and said cylinder being provided with a loading door and a clean out door to permit access to the baffle means through the cylinder.

13. A machine of the character described, comprising a casing, a rotatable cylinder therein, said casing being provided with a dirt collecting recess below the cylinder, baffle means therein arranged to retard agitation of the cleaning fluid, and two drain openings for said casing, one located at the level of the upper portion of said baffle means and the other at the bottom of said recess, the first opening being adapted to drain the cleansing fluid without disturbing the fluid in said recess and the second opening being adapted to flush out the recess.

14. In a machine of the character described, the combination of a fluid receiving casing having a substantially vertical chamber, a work receiving cylinder rotatably mounted in said chamber, said casing being also provided with a trough beneath said cylinder with the space within said trough communicating with said chamber, and means in said trough for retarding agitation of the treating fluid in said trough, said means being so positioned in said trough that it constitutes a continuation of the cylindrical wall of said casing.

In testimony whereof I hereby affix my signature.

IVAN M. TULL.

- cleaning fluid outside of said cylinder, said baffle means including an open-end frame, baffle plates, and means for removably locking said plates in said frame upon application thereto through the open end of said frame, said baffle means being spaced from said cylinder so as to permit application and removal of said plates. 5
9. In a device of the class described, a baffle means comprising an open-end frame having slotted transverse baffle plates, and tapered longitudinal baffle plates adapted to be applied through the open end of said frame and to have their tapered end portions 10 seat in the slots of said transverse plates, and said longitudinal plates being provided with slots for interlocking engagement at their other ends with the slots of said transverse plates. 15
10. A machine of the character described, comprising a casing, a rotatable cylinder therein, and baffle means within the casing below the cylinder adapted to retard agitation of the cleansing fluid, said cylinder being provided with a loading door and a clean out door providing access through the cylinder to said baffle means. 20
11. A machine of the character described, comprising a casing, a rotatable cylinder therein, said casing being provided with a trough forming a chamber beneath the cylinder, baffle means in said chamber, and said cylinder being provided with a loading door and a clean out door permitting access 25 through the cylinder to said chamber. 30
12. A machine of the character described, comprising a casing, a rotatable cylinder 35
- therein, and baffle means within the casing below the cylinder, said casing being provided in a side wall with an opening through which said baffle means may be horizontally removed, and said cylinder being provided with a loading door and a clean out door to permit access to the baffle means through the cylinder. 40
13. A machine of the character described, comprising a casing, a rotatable cylinder therein, said casing being provided with a dirt collecting recess below the cylinder, baffle means therein arranged to retard agitation of the cleaning fluid, and two drain openings for said casing, one located at the level of the upper portion of said baffle means and the other at the bottom of said recess, the first opening being adapted to drain the cleansing fluid without disturbing the fluid in said recess and the second opening being adapted to flush out the recess. 45
14. In a machine of the character described, the combination of a fluid receiving casing having a substantially vertical chamber, a work receiving cylinder rotatably mounted in said chamber, said casing being also provided with a trough beneath said cylinder with the space within said trough communicating with said chamber, and means in said trough for retarding agitation of the treating fluid in said trough, said means being so positioned in said trough that it constitutes a continuation of the cylindrical wall of said casing. 50
15. In testimony whereof I hereby affix my signature. 55
